COMBINED ELECTRICAL LOAD RECORDER AND METER

Murray C. Carney, Springfield, Ill., assignor to Sangamo
Electric Company, Springfield, Ill.

Filed Jan. 10, 1973, Ser. No. 322,380

Term of patent 14 years

Int. Cl. D10—05

U.S. Cl. D10—75

FIG. 1 is a front elevational view of a combined electrical load recorder and meter showing my new design;
 FIG. 2 is a right side elevational view thereof;
 FIG. 3 is a top plan view thereof;
 FIG. 4 is a left side elevational view thereof;
 FIG. 5 is a rear elevational view thereof;
 FIG. 6 is a bottom plan view thereof.

I claim:

The ornamental design for a combined electrical load recorder and meter, substantially as shown and described.
